D. P. Hollaway, Esq.
his atty.

United States Patent Office.

HENRY ANSLEY, OF WASHINGTON, DISTRICT OF COLUMBIA.

Letters Patent No. 80,699, dated August 4, 1868.

IMPROVEMENT IN BUTTONS.

The Schedule referred to in these Letters Patent and making part of the same.

TO ALL WHOM IT MAY CONCERN:

Be it known that I, HENRY ANSLEY, of Washington, in the District of Columbia, have invented a new and useful Improvement in Sleeve-Buttons; and I do hereby declare that the following is a full, clear, and exact description of the same, reference being had to the annexed drawings, making part of this specification, in which—

Figure 1 is a perspective view, and

Figure 2 is a side elevation.

The same letters are employed in both figures in the designation of the same parts.

A, in the annexed drawings, is the outer disk of the button; B is the shank, and C a coil, forming the inner part of the button: It is fastened to the shank by a cross-brace, C'.

The shank is attached at the centre of the outer disk A, and the cross-brace C' is attached at both ends to the coil, the latter being extended, so as to make one revolution and a half of the button in inserting it into the button-hole.

The button is inserted by passing the outer point of the coil through the button-hole, and turning it until the coil has passed through the button-holes. As it is only necessary that the length of the button-hole should be the semi-diameter of the coil, plus the semi-diameter of shank, it is apparent that the button cannot be lost out of the button-hole, as it can only be withdrawn by unscrewing it.

The article may be used for either a sleeve-button or as a shirt-stud.

What I claim as my invention, and desire to secure by Letters Patent, is—

A button or stud, constructed with the parts A, B, C, and C', arranged in relation to one another, substantially as described.

In testimony whereof, I have signed my name to this specification in the presence of two subscribing witnesses.

Witnesses:

JOHN S. HOLLINGSHEAD.

HENRY ANSLEY.
